DETERGENT COMPOSITIONS

Richard D. Stayner, Berkeley, Calif., assignor to California Research Corporation, San Francisco, Calif., a corporation of Delaware

No Drawing. Application February 13, 1953,
Serial No. 336,889

6 Claims. (Cl. 252—137)

This invention relates to improved anionic synthetic detergent compositions containing as their only effective detergent ingredient a water-soluble alkyl aryl sulfonate. More particularly, the invention relates to those synthetic detergent compositions which contain a water-soluble alkyl benzene sulfonate as their sole effective ingredient, and which produce persistent foams of good quality when employed in dilute aqueous solutions to wash soiled fabrics.

The average user of detergents insists on buying detergent materials capable of producing a substantial volume of suds, owing to a deeply ingrained belief that the formation of copious suds or foam is always accompanied by a good detergent action. The majority of users of detergent products, whether housewives or commercial laundry operators, continue to prefer those materials which produce a dense foam made up by small-size bubbles and giving the familiar feeling of cream-like soapsuds on contact with the hand.

Because at the present time a large volume of household washing is done by housewives in non-automatic, agitator-type washing machines, the ability of a detergent composition to produce stable foam under static conditions is not a criterion that it would secure a lasting preference of the consumer. Actually the foam, in addition to being similar in physical appearance to soapsuds, must be persistent throughout the washing cycle, despite the continuous agitation of the contents of the bowl or tub of the washing machine, the presence of soil, laundry, etc. At low use concentrations in soft water, this requirement of foam persistence cannot, as a rule, be attained in the case of alkyl aryl sulfonate type detergents, and this inability of producing persistent foams is best exemplified in the use of sodium salts of C₉—C₁₈ monalkyl benzene sulfonic acids, otherwise very efficient as detergents. As a matter of fact, the suds produced with solutions of detergent compositions containing such sulfonates as their major active ingredients are extremely short-lived and last but a few minutes, usually from 1 to less than 10 minutes depending upon such factors as: hardness of water, amount of the active sulfonate in the formulation, type and amount of soil present, concentration of the wash solution and temperature of this latter.

The C₉—C₁₈ monoalkyl benzene sulfonates, the improvement of foam properties whereof is particularly considered in the present specification, are usually prepared by reacting benzene with a long-chain C₉—C₁₈ aliphatic alcohol, or with a C₉—C₁₈ olefin produced, for instance, by cracking petroleum hydrocarbon gases and polymerizing the gaseous olefins thus formed, or with an alkyl halide obtained by chlorinating petroleum hydrocarbons of the boiling range of kerosene; sulfonating the resulting alkyl benzene compounds with sulfuric acid, chlorosulfonic acid or sulfur trioxide; neutralizing the resulting sulfonic acid with a base (e. g., NaOH or Na₂CO₃); and, finally, drying the neutralized slurry product (e. g., by spray-drying) to the desired particle form and size. Detergent compositions containing sodium C₉—C₁₈ alkyl ben-

2

zene sulfonate as their major organic detergent ingredient ordinarily contain, in addition, from 50 to 90% by weight of inorganic alkaline builders such as polyphosphates and/or sodium sulfate. In the conventional sodium alkyl benzene sulfonate detergent compositions employed for laundering and household washing, from 20 to 50% by weight of these inorganic alkaline builder constituents is constituted by sodium sulfate, which is either present in the product as a result of the neutralization of unreacted sulfuric acid in the sulfonation reaction mixture, or is added to suit the particular detergent product specification. The balance of the builder portion, from 80 to 20% by weight thereof, is either sodium tripolyphosphate or tetrasodium pyrophosphate, or a mixture of the two in any appropriate weight ratio. Usually, sodium silicate builders in amounts of the order of 5% by weight of the total solids are present in these detergent formulations. In addition, these sulfonate detergent compositions may contain other conventional additives such as sodium carboxymethyl cellulose extender, optical bleach, perfume, etc. in small amounts readily determined by those skilled in the art to suit the requirements of each particular formulation.

A number of additives have been proposed in the past for the purpose of promoting foam formation in aqueous wash solutions of alkyl benzene sulfonate detergent compositions and imparting the desired persistence to this foam. For instance, small amounts of alkylol amides of fatty acids, e. g., isopropanol amide of lauric acid and ethanol amide of lauric acid, have been blended into these sulfonate detergent compositions. However, while their addition improved the desired foam persistence, their presence in the sulfonate detergent product caused stickiness and caking of the particles during the spray-drying step of the detergent manufacture and in the storage of the finished particulate product. Furthermore, foams produced by the alkyl benzene sulfonate detergent compositions containing such amides do not attain the desired quality of soapsuds with respect to color, size of the bubbles, flexibility and wetness. N-alkyl- β -alanines have been suggested as foam stabilizers. However, the presence of these alanines in alkyl benzene sulfonate detergent compositions causes a reduction in the detergent power thereof, and their application must be, therefore, ruled out.

I have now found that very satisfactory foam characteristics can be imparted to a detergent composition, in which the major active organic detergent ingredient is a water-soluble alkyl benzene sulfonate in the amount equal to from 10 to 50% by weight of the total content of solids, by introducing into such a composition a small quantity of N-alkyl imino-diacetic acid wherein the alkyl chain contains from 8 to 18 carbon atoms. Very satisfactory foams can be obtained with the aqueous solutions of detergent compositions wherein the predominant organic detergent ingredient is an alkyl benzene sulfonate, containing from 0.5 to 10% by weight of N-alkyl imino-diacetic acid additives, based on the total content of solids (or from 5 to 20% based on the weight of the active sulfonate ingredient), not only with respect to the volume and quality thereof, but also with respect to its persistence throughout the entire agitation cycle in the washing machine. The greater is the concentration of the additive in the detergent composition, the better is the foam persistence. In general, an abundant foam of good quality and a high degree of persistence can be obtained by adding to the alkyl benzene detergent composition from 2 to 4% (by weight of the total solids) of an N-alkyl imino-diacetic acid, though smaller or greater amounts may be required with varying water hardness, concentration and temperature and quantities of individual ingredients within the disclosed operative ranges thereof.

This additive, which for the sake of brevity, will be termed hereafter "N-alkyl diglycine," is soluble in water and nonvolatile, both of these properties representing a decided advantage over the previously proposed additives of the art.

The N-alkyl diglycine is added to the sulfonate detergent compositions in the form of water-soluble alkaline salts, i. e., inorganic alkali metal salts, inorganic alkaline earth metal salts such as magnesium salts, ammonium salts and organic alkyl ammonium and alkylol ammonium salts. Alkali metal salts are preferably employed, sodium salt of N-alkyl imino-diacetic acids being most effective in compositions containing sodium C₉-C₁₈ monoalkyl benzene sulfonate as the major organic detergent ingredient.

This sodium salt is easily prepared by a simple one-step reaction of a straight-chain C₈-C₁₈ alkyl amine with sodium chloroacetate. An excellent source of fatty amines for the preparation of effective N-alkyl diglycines is offered by coconut fatty acid amines ordinarily containing about 15% of amines with less than 12 carbon atoms in the alkyl chain, about 45% of C₁₂ amine, and about 40% of amines with more than 12 carbon atoms in the alkyl chain. I have found that while generally water-soluble alkaline salts of N-alkyl diglycines containing from C₈-C₁₈ carbons in the alkyl chain will secure the desired improvement in the foam properties of an alkyl benzene sulfonate detergent composition, particularly satisfactory results will be obtained with water-soluble alkaline salts of N-alkyl diglycines containing from 10 to 16 carbon atoms in the alkyl chain, the best results being secured with water-soluble alkaline salts of N-alkyl diglycines containing from 12 to 14 carbon atoms in the alkyl chain.

The N-alkyl diglycine may be introduced into the sulfonate detergent composition either before the neutralization of the sulfonic acid-unreacted sulfuric acid mixture or it may be added as a corresponding water-soluble salt to the neutralized slurry, this last technique being preferred. Upon blending of the additive with the neutralized slurry, the mixture is reduced to the desired particle size and foam, e. g., by spray-drying. The N-alkyl diglycine may be also added to alkyl benzene sulfonate detergent essentially free of inorganic salts and formulated as concentrated liquids with water or other appropriate solvents.

As pointed out hereinbefore, the alkyl benzene sulfonate detergent compositions, foam properties of which can be improved by the addition of N-alkyl diglycine additives according to the invention, may contain from 10 to 50% by weight of organic detergent ingredients, at least 50% whereof is constituted by a water-soluble salt of a C₉-C₁₈ monoalkyl benzene sulfonic acid, and preferably of a C₁₂-C₁₅ monoalkyl benzene sulfonic acid, and preferably of a C₁₂-C₁₅ monoalkyl benzene sulfonic acid. The term "water-soluble salt" employed hereinabove includes inorganic alkaline metal salts, alkaline earth metal salts such as magnesium, ammonium salts, and organic alkyl amine and alkylol amine salts, exemplified by triethanol and diethanol amine salts. Minor amounts of anionic and non-ionic organic detergents may be present in the formulations, the foam persistence of which is improved by the addition of N-alkyl diglycines, e. g., alkyl sulfates, polyglycol ethers of alkyl phenols. Ordinarily, the alkyl benzene sulfonate detergent compositions containing an N-alkyl diglycine additive are dissolved in water to form solutions of 0.1 to 0.4% concentration, conventionally employed in the laundering practice, and produce satisfactory persistent foams. When the additive is present in the wash solution as a sodium salt of N-alkyl imino-diacetic acid, it is either in the form of monosodium salt (when the solution is neutral) or in the form of disodium salt (when the solution is alkaline).

When the so-called "heavy-duty" all purpose alkyl benzene sulfonate detergent compositions containing from 10 to 35, and preferably from 15 to 30, parts by weight of active organic detergent sulfonate in each 100 parts of

solid constituents thereof, have received an addition of N-alkyl diglycine in the amounts of from 0.5 to 10%, and preferably from 2 to 4%, based on the weight of the total solids, the aqueous wash solutions of these heavy-duty compositions in non-automatic, agitator-type washing machines form dense, soap-like suds, which persist throughout the entire washing cycle, i. e., up to 20 minutes and often longer.

The flexible texture of the foams thus produced resembles that of the better fatty acid soaps: They are light in color, and are made up of small-size bubbles aggregated to a cream-like consistency. In contrast to a number of other anionic detergent compositions, the foams produced by alkyl benzene sulfonate detergent compositions improved in accordance with my invention do not build up a stiff central ring of dry and frosty foam around the agitator shaft in the tub of the washing machine. Furthermore, the presence of an N-alkyl diglycine additive imparts a slippery, soap-like "feel" to the wash solution, a property sought for by the housewife.

Moreover, a highly attractive characteristic of the improved detergent composition of the invention is its emollient effect upon the skin of the operator due to the presence of the N-alkyl diglycine additive. Whereas quite often housewives and laundry workers handling anionic detergent compositions complain of their drying action which sequesters oil from the skin and causes cracking and fissuring thereof, this adverse action has not been observed in the numerous test runs effected with the alkyl benzene sulfonate compositions containing salts of N-alkyl diglycines in accordance with the present invention.

Several series of test runs were carried out to evaluate the quality and persistence of foams produced by alkyl benzene sulfonate detergent compositions containing N-alkyl diglycine additives in accordance with the invention.

In a representative test series, the N-alkyl imino-diacetic acid additive (N-alkyl diglycine) was prepared as follows: 51 g. of lauryl amine, 21 g. of NaHCO₃, and 25 ml. of isopropanol were placed in a 500 ml. round-bottomed flask equipped with a thermometer, stirrer and addition funnel. The mixture was heated to 150° F., whereupon a solution of 59 g. of sodium chloroacetate in 75 ml. of water was added dropwise for a period of about 15 minutes, taking care to maintain the temperature without heating at 150-175° F. Upon completing the addition, the solution was refluxed for at least 3 hours until the evolution of CO₂ ceased. The final solution (165 g.) contained 85 g. of N-lauryl imino-diacetic acid as the monosodium salt at pH 7.5. The sulfonate detergent composition employed in this test series contained sodium C₁₂-C₁₅ polypropylene benzene sulfonate (prepared by the process disclosed by A. H. Lewis in U. S. Patent #2,477,383) as its sole organic detergent ingredient in an amount from 20 to 30% by weight, from 2 to 3% by weight of N-lauryl diglycine, the remainder to make up 100% being sodium tripolyphosphate (or a mixture of sodium tripolyphosphate and tetrasodium pyrophosphate) and sodium sulfate. The tests consisted in agitating identical loads of soiled cotton laundry in the bowl of an agitator-type non-automatic domestic washing machine filled with a dilute aqueous solution of the detergent containing an effective amount of an N-alkyl diglycine additive. Solutions of 0.15% concentration of these detergent formulations in soft water (50 p. p. m.; CaCO₃=2:1) were maintained at the same temperature throughout the test runs, and the agitation was carried out in each instance for 20 minutes under identical conditions.

The results of this series of test runs are tabulated in Table I. Persistence of the foam after 2, 5, 10, 15 and 20 minutes of operation is defined in terms of foam height (in inches) and coverage, i. e., the extent of the tub surface covered by the foam, in per cent. The data in the table clearly show that detergent compositions without N-alkyl diglycine additives have extremely poor

foam persistence or none at all. On the other hand, dilute aqueous solutions of those detergent compositions which contain the diglycine additive display excellent foam persistence, and the foam produced by these wash solutions lasts 20 minutes and longer, without substantial reduction of volume or alteration of foam quality, in spite of the continuous agitation in the washing machine. The data also show that other glycine type compounds such as N-lauryl monoglycine, N-lauryl- β -alanine, N-lauryl-N, N-dicarboxymethyl glycine betaine (N-lauryl "triglycine"), N-lauryl-N, N-dimethyl glycine betaine either produce foam of a low degree of persistence or, as shown by run #18 with N-benzyl-N, N-dimethyl glycine betaine, produce practically no foam.

In addition, detergency was determined for formulations employed in the foam-persistence evaluation series of Table I, in a conventional agitator-type automatic washing machine, employing solutions of different concentrations and having the same temperature, in both soft water (50 p. p. m.; CaCO_3 : MgCO_3 =2:1) and hard water (300 p. p. m.; CaCO_3 : MgCO_3 =2:1). In each instance, the automatic washer was charged with a load of clean

10
15

20
25

cotton towels, to each of which had been pinned a strip of cotton, uniformly soiled with an oily soil. In each test run agitation was carried out for the same length of time and under identical conditions. After the completion of each test run, the swatches were removed, and the degree of whiteness (detergency) obtained was measured in a photoelectric apparatus free of human equation. This detergency was rated with reference to an arbitrarily chosen standard, assumed to be equal 100%, namely, the degree of whiteness obtained with a 0.4% solution in hard water (300 p. p. m.) of a well-known, substantially pure fatty acid soap (derived from a mixture of coconut fatty acids and tallow fatty acids).

The results of several representative runs in this series of detergency determinations are tabulated in Table II, and indicate that the presence of N-alkyl diglycine does not impair detergency, while the presence of N-lauryl- β -alanine definitely has an adverse effect thereon. Blends of tetrasodium pyrophosphate and sodium tripolyphosphate, employed in lieu of sodium tripolyphosphate alone as the phosphate builder in alkyl benzene sulfonate detergent compositions appear to improve detergency.

Size of the foam bubbles and the feel, or "body" of the foam produced by sulfonate detergent formulations containing an N-alkyl diglycine, favorably compare with the creamy dense suds, made up of small-size bubbles, produced by a 0.25% solution of a phosphate-built tallow fatty acid soap (run #23 of the table) and are definitely superior to lacy, rapidly decaying foam of alkyl benzene sulfonate detergent compositions which did not contain diglycine additives (runs #1, 3, 5, 7, 9 of the table).

Wetness and mobility of the foam are likewise satisfactory: samples, placed upon a vertical glass surface, slide down rapidly as compared to several samples of foams produced by dilute solutions of commercial alkyl sulfate-alkyl benzene sulfonate detergent compositions which appear to be dry and frosty, and cling to the glass surface.

Increasing water hardness appears to increase the foam persistence, and the like effect is observed on replacing sodium sulfate builder in the sulfonate detergent composition by magnesium sulfate. However, in either instance, the detergency of the wash solution is adversely affected, and a greater concentration of the active detergent sulfonate component may be required.

At this point, it may be noted that it is possible to combine with advantage into the same sulfonate detergent formulation an N-alkyl diglycine additive which improves foam persistence and foam quality with alkylol amides of higher fatty acids, such as isopropanol amide of lauric acid or ethanol amide of lauric acid, which, in addition to being good foaming agents, tend to enhance detergency. Heretofore, it was impossible to spray-dry a neutralized slurry of alkyl benzene sulfonate containing 25% by weight or more (based on the total solids) of the active sulfonate detergent and as little as 2% by weight of an alkylol amide of a higher fatty acid, without running into the problems of: (1) stickiness in the spray-drying step (the material adheres to the walls of the spray-drying chamber instead of readily dropping into the hopper); and (2) caking upon storage of the spray-dried product. For instance, the neutralized slurry containing 20% by weight of sodium alkyl benzene sulfonate and 2% by weight of isopropanol amide of lauric acids was difficult to spray-dry, and upon prolonged storage in a humid atmosphere caked badly, and failed to pass the required specifications. On the other hand, a slurry containing 30% by weight of sodium alkyl benzene sulfonate and 3% by weight of the sodium salt of N-lauryl diglycine presented no problem in the course of spray-drying and satisfactorily passed the caking specification after similar storage in a humid atmosphere. Thus, by a proper selection of the two foam improving additives (N-alkyl diglycine and alkylol amide of a higher fatty acid), it will be possible to eliminate the aforementioned difficulties of

manufacturing and storage and to impart better properties to sulfonate detergent formulations, so as to make them more attractive for the consumer.

It is to be understood that the aforesigned description and experimental data are merely illustrative of the invention, and that it may be modified without essential departure from the spirit and scope thereof, provided that such modifications fall within the scope of the appended claims.

I claim:

1. A detergent composition, characterized by a high degree of persistence of its foam under conditions of agitation in dilute aqueous solutions, consisting essentially of from 10 to 50% by weight, based on the total content of solids in said composition, of a water-soluble salt of a C₉-C₁₈ monoalkyl benzene sulfonic acid as its major organic detergent ingredient, from 0.5 to 10% of a water-soluble salt of an N-alkyl imino-diacetic acid wherein the alkyl group contains from 10 to 16 carbon atoms, the remainder to make up 100% being essentially inorganic salt detergent builders.
2. A detergent composition, characterized by a high degree of persistence of its foam under conditions of agitation in dilute aqueous solutions, consisting essentially of from 10 to 35% by weight, based on the total content of solids in said composition, of a water-soluble salt of a C₉-C₁₈ monoalkyl benzene sulfonic acid as its major organic detergent ingredient, from 2 to 4% of a water-soluble salt of an N-alkyl imino-diacetic acid wherein the alkyl group contains from 10 to 16 carbon atoms, and the remainder to make up 100% being essentially inorganic salt detergent builders.
3. A detergent composition, characterized by a high degree of persistence of its foam under conditions of agitation in dilute aqueous solutions, consisting essentially of from 10 to 50% by weight, based on the total content of solids in said composition, of a water-soluble salt of a C₉-C₁₈ monoalkyl benzene sulfonic acid as its major organic detergent ingredient, from 0.5 to 10% of a water-soluble salt of an N-alkyl imino-diacetic acid wherein the alkyl group contains from 10 to 16 carbon atoms, and the remainder to make up 100% being essentially inorganic salt detergent builders, of which from 10 to 50% is sodium sulfate.
4. A detergent composition, characterized by a high degree of persistence of its foam under conditions of agitation in dilute aqueous solutions, consisting essentially of from 10 to 50% by weight, based on the total content of solids in said composition, of a water-soluble salt of a C₉-C₁₈ monoalkyl benzene sulfonic acid as its major organic detergent ingredient, from 0.5 to 10% of a water-soluble salt of an N-alkyl imino-diacetic acid wherein the alkyl group contains from 10 to 16 carbon atoms, from 10 to 45% of sodium sulfate builder, and the remainder to make up 100% being essentially inorganic alkaline polyphosphate builders.
5. A detergent composition, characterized by a high degree of persistence of its foam under conditions of agitation in dilute aqueous solutions, consisting essentially of from 10 to 50% by weight, based on the total content of solids in said composition, of a water-soluble salt of a C₉-C₁₈ monoalkyl benzene sulfonic acid as its major organic detergent ingredient, from 0.5 to 10% of a water-soluble salt of an N-alkyl imino-diacetic acid wherein the alkyl group contains from 10 to 16 carbon atoms, from 10 to 45% of sodium sulfate builder, and the remainder being essentially a mixture of sodium tripolyphosphate and tetrasodium pyrophosphate.
6. A detergent composition, characterized by a high degree of persistence of the foam of its dilute aqueous solutions under conditions of agitation and in the presence of soil, said composition consisting essentially of a water-soluble salt of a C₉-C₁₈ monoalkyl benzene sulfonic acid as its major organic detergent ingredient

normally tending to sequester oil from human skin and to cause irritation thereof, and from 5 to 20%, based on the weight of said sulfonic acid salt, of a water-soluble salt of an N-alkyl imino diacetic acid, in which the alkyl group contains from 10 to 16 carbon atoms as a foam 5 persistence improver and an inhibitor of skin irritation.
